UNITED STATES PATENT OFFICE

108,045

DESIGN FOR AN ELECTRIC WELDING APPARATUS

James W. Wilkinson, deceased, late of Kansas City, Kans., by Gladys M. Wilkinson, executrix, Johnson, Kans.

Application May 10, 1937, Serial No. 69,276

Term of patent 7 years

To all whom it may concern:

Be it known that James W. Wilkinson, deceased, late a citizen of the United States and a resident of Kansas City, Wyandotte County, Kansas, invented a new, original, and ornamental Design for an Electric Welding Apparatus, of which the following is a specification, reference being had to the accompanying drawing, forming a part thereof.

In the drawing:—

Figure 1 is a perspective view of an electric welding apparatus, showing the new design.

Figure 2 is a side elevation of the apparatus, showing the side opposite that shown in Figure 1.

Figure 3 is an end view of the apparatus, showing the end opposite that shown in Figure 1.

In the drawing the dominant features are shown in heavy black lines, the device being particularly characterized by its unbroken cylindrical shape from end to end and its reticulated convex guards closing its opposite ends.

What is claimed is:

The ornamental design for an electric welding apparatus as shown and described.

GLADYS M. WILKINSON,
*Executrix of the Estate of James W. Wilkinson,
Deceased.*
